APPARATUS PRODUCING HIGH-POWERED SOUNDS AND ULTRA-SOUNDS

Vladimir Gavreau, Marseille, France, assignor to Centre National de la Recherche Scientifique, Paris, France, a French society

Application February 28, 1955, Serial No. 491,089

Claims priority, application France March 2, 1954

3 Claims. (Cl. 116—137)

The present invention relates to apparatus for emitting sounds or ultra-sounds in a liquid mass.

Up to this time the apparatus used for this purpose were capable of transmitting but very little energy into the liquid mass. The power developed by quartz or magnetostriction apparatus is very limited and the sounds produced by sirens, which are powerful, practically do not penetrate liquids.

The object of the present invention is to obviate this difficulty.

For this purpose the apparatus according to my invention includes a chamber separated from the mass of liquid by a flexible diaphragm and means for producing in said chamber a succession of pressure oscillations, said means, which include a rotary distributing valve device, intermittently and repeatedly placing said chamber in communication with a discharge space at a frequency of repetition within the range of sound and ultra-sound frequencies, through at least one orifice and introducing into said chamber, through said orifice a gaseous fluid at a pressure higher than that existing in said discharge space during every period between two successive time periods for which said chamber is in communication with said discharge space, said means being arranged to close said orifice for a short time between every period of introduction of gaseous fluid into said chamber and the next period of communication of said chamber with said discharge space, during which short time said chamber is wholly closed.

Preferred embodiments of my invention will be hereinafter described with reference to the accompanying drawings, given merely by way of example and in which:

Fig. 1 is an axial section of an apparatus made according to a first embodiment of my invention, the right-hand half of this figure showing a relative position of the parts slightly different from that shown by the left-hand half.

Fig. 2 is a similar view of an apparatus made according to another embodiment of said invention.

The apparatus shown by Fig. 1 includes a fixed casing C on the top of which is fixed a container 11—32 with a mass of liquid 33 therein. The top plate of casing C is provided with a circular row of holes 9 which are separated from the liquid 33 by a diaphragm 26 held between casing C and container 11—32.

In casing C and in a hub 12 fixed thereto, there is journalled, at 19 and 20 (18 being a packing box), a shaft 17 carrying a rotor made of two parts 51 and 52 rigid with each other. This rotor divides the inside of casing C into two coaxial compartments 24 and 30. Compartment 24 communicates through a conduit 27 with

2

a source of compressed air. Compartment 30 communicates through a conduit 31 with the atmosphere or any other discharge space. The rotor 51—52 is provided with a circular row of passages, the total number of said passages being equal to twice the number of holes 9. Every second passage 281—282 extends between compartment 24 and the under face of the top plate of casing C. The other passages 291—292 (each located in a radial plane of the rotor located between two radial planes corresponding to two consecutive passages 281—282) extend between the under face of said top plate of casing C and the other compartment 30. The portions 282, 291 of these passages are located at the same distance from the axis of rotation of shaft 17.

During the rotation of rotor 51—52 there is a position (shown by the left-hand half of Fig. 1) for which all the passages 281—282 are in register with holes 9 which are then filled with compressed air from conduit 27 so that a substantial pressure is exerted on diaphragm 26. Then the rotor, after further rotation through a small angle, during which holes 9 communicate neither with passages 281—282 nor with passages 291—292, passes through a position (shown by the right-hand side of Fig. 2) where holes 9 are placed in communication, through passages 291—292, with compartment 30 and discharge pipe 31 so that there is a sudden drop of the pressure exerted on diaphragm 26.

The air pressure at 27 may be one or several kilograms per square centimeter; the discharge pressure at 31 may be of the order of magnitude of 1 kg./cm.², or more, if, for example, the apparatus is used for the transmission of under water of sound signals at a substantial depth or if a pressure higher than atmospheric pressure exists in the container 11—32 where the liquid is to be treated. Within holes 9, the pressure rapidly attains a value close to that of the feed pressure, then drops as quickly. Thus the air pressure within holes 9 oscillates with an amplitude of several kg./cm.² and these substantial pressure variations are transmitted to the liquid through diaphragm 26.

It is known that the variations of instantaneous pressure corresponding to sound waves transmitted in the atmosphere are of the order of several grams per cm.², while in order to produce sound waves of the same intensity in liquids, pressures of several kilograms per cm.² must be used. Thus a given acoustic intensity (in watt/cm.²) in the atmosphere corresponds to pressures in water 59 times greater (and to amplitudes 59 times smaller).

For this reason, an absolutely negligible portion of the sounds transmitted by the air of the atmosphere can penetrate liquids, and until the present the use of sirens for the acoustic treatment of liquids (ultra-sound treatment, for example) has not been successful. If sound or ultra-sound waves are applied to a thin sheet of liquid falling freely through space, this sheet will vibrate as a whole without, however, the sound being able to penetrate it. And the only effect that can be obtained by this means is a pulverization having nothing in common with the different useful effects produced by ultra-sounds transmitted into the very interior of a liquid mass.

Experiment shows that the strong compressions and depressions produced in the holes 9 of the apparatus of Fig. 1 achieve the transmission of very intense sounds in the liquid mass. An important cause of the poor over-all efficiency of sirens is loss charge in the compressed air pipes and the generally poor output of air compressors.

Moreover, the compression and decompression of air, notably in the pressure reducer and the siren itself, causes troublesome condensations of water and oil, making it necessary to use "dryers" and "de-oilers" which in turn are responsible for further pressure losses.

To reduce these drawbacks (within the scope of the present invention) any other compressed gas can be used instead of air; this compressed gas may be introduced into suitably located chamber or chambers in the stator or rotor, in the form of a mixture of a combustible gas or vapor with air or oxygen, the desired pressures in said chamber being developed by combustion or explosions of this mixture therein.

For this purpose I may make use of an apparatus as shown by Fig. 2.

The general arrangement is the same as that of Fig. 1. But holes 9 communicate with a chamber 35 separated from the liquid mass 33 by diaphragm 26. In this chamber 35 is provided a spark plug 34 operated, in a conventional fashion, to give a spark every time the rotor 51-52, after placing holes 9 and chamber 35 in communication with a carburetor mounted on pipe 27, has just cut off said communication. Furthermore a suction is exerted in compartment 30 by a pump mounted on pipe 31.

It is evident that under these conditions four phases in the operation of this siren can be distinguished:

1st phase.—The chamber 35 being in communication, through pipe 31, with the suction pump, a depression is formed therein.

2nd phase.—Communication is cut off between chamber 35 and passages 29₁-29₂.

3rd phase.—Immediately thereafter, chamber 35 comes into communication with the feed tube 27, by means of the vertical passages 28₁-28₂ of rotor 51-52.

4th phase.—The rotor further turns (driven by an electric motor) and passages 28₁-28₂ are closed. The ignition is timed for this moment. A certain degree of pressure (on the order of several kg./cm.²), exactly as in the explosion motor of a motorcycle or automobile, is exerted against diaphragm 26 which, itself, practically does not move, being held in place by the liquid 33 contained in the reservoir 11-32 on the other side of the membrane. The interior of chamber 35 is then again placed in communication with the suction pump by means of tube 31 and passages 29₁-29₂. The gases resulting from the combustion (or explosion) are evacuated by this suction pump and the cycle begins again.

In a general manner, while I have, in the above description, disclosed what I deem to be practical and efficient embodiments of my invention, it should be well understood that I do not wish to be limited thereto as there might be changes made in the arrangement, disposition and form of the parts without departing from the principle of the present invention as comprehended within the scope of the accompanying claims.

What I claim is:

1. An apparatus for emitting sounds or ultra-sounds in a liquid mass which comprises, in combination, a container for said liquid mass having a portion of its wall constituted by a flexible diaphragm, a fixed structure forming at least one gas chamber contiguous to said container along at least a portion of said diaphragm, which thus forms a thin and flexible partition between said chamber and said liquid mass, said gas chamber having at least one orifice, a rotary distributing valve device for intermittently and repeatedly placing said chamber in communication through said orifice with a discharge space, at a frequency of repetition within the range of sound and ultra-sound frequencies, and means including said distributing valve device for introducing into said chamber through said orifice a gaseous fluid at a pressure higher than that in said discharge space during every period between every two successive time periods where said chamber is in communication with said discharge space, said means being arranged to close said orifice for

a short time between every period of introduction of gaseous fluid into said chamber and the next period of communication of said chamber with said discharge space, during which short time said chamber is wholly closed.

2. An apparatus for emitting sounds or ultra-sounds in a liquid mass which comprises, in combination, a container for said liquid mass having a portion of its wall constituted by a flexible diaphragm, a fixed structure including a plate provided with a multiplicity of holes disposed in a circular row, said holes extending throughout said plate and said flexible diaphragm being located adjacent to said plate on one face thereof, whereby said holes form gas chambers limited on one face of said plate by said diaphragm, each of said chambers having one orifice opening into the other face of said plate, conduit means leading to a discharge space, a source of gaseous fluid at a pressure higher than that in said discharge space, and distributing means including a casing in the form of a body of revolution about an axis at right angles to said plate and passing through the center of said circular row of holes, said casing forming two concentric compartments, one in communication with said source and the other with said conduit means leading to said discharge space, and a rotor journaled about said axis having a flat face adjoining said plate on the second mentioned face thereof and including a multiplicity of passages, every second passage of said rotor being arranged, for a given position of said rotor about its axis to register with one of said orifices so as to connect said first mentioned compartment with one of said chambers whereby all of said chambers are then fed with gaseous fluid from said source, and every other passage of said rotor being arranged to connect, after a small rotation of said rotor, one of the same orifices with said second mentioned compartment, whereby all of said chambers are then in communication with said discharge space, the speed of rotation of said rotor and the number of said holes being chosen to achieve a frequency of repetition of the feed of said gaseous fluid to said chamber within the range of sound and ultra-sound frequencies.

3. An apparatus for emitting sounds or ultra-sounds in a liquid mass which comprises, in combination, a container for said liquid mass having a portion of its wall constituted by a flexible diaphragm, a fixed structure forming a gas chamber contiguous to said container along at least a portion of said diaphragm which thus form a thin and flexible partition between said liquid mass and one end of said chamber, said structure further including, at the other end of said chamber, a plate provided with a multiplicity of holes disposed in a circular row, said holes extending throughout said plate, conduit means leading to a discharge space, means for supplying a carbureted mixture of fuel and combustible at a pressure higher than that in said discharge space, distributing means including a casing in the form of a body of revolution about an axis at right angles to said plate and passing through the center of said circular row of holes, said casing forming two concentric compartments, one in communication with said carbureted mixture supplying means and the other with said conduit means leading to said discharge space, and a rotor journaled about said axis having a flat face adjoining said plate on the face thereof opposed to that located in said chamber, said plate including a multiplicity of passages, every second passage of said rotor being arranged, for a given position of said rotor about its axis, to register with one of said holes so as to connect said first mentioned compartment with said chamber whereby said chamber is then fed with said carbureted mixture, and every other passage of said rotor being arranged to connect, after a small rotation of said rotor, one of the same holes with said second mentioned compartment, whereby said chamber is then in communication with said discharge space, and means in said chamber operative in synchronism with the rotation of said

rotor for igniting said mixture in said chamber when said holes are closed by said rotor, the speed of rotation of said rotor and the number of said holes being chosen to achieve a frequency of repetition of the successive ignitions within the range of sound and ultra-sound frequencies.
